Application August 23, 1944, Serial No. 550,764
In Great Britain August 22, 1942

42 Claims. (Cl. 12—80)

This invention relates to apparatus for use in applying adhesive to shoe parts and is illustrated herein as embodied in a counter pasting machine of the type in which a shoe counter is automatically presented to rotary coating-applying brushes.

In the manufacture of shoes it is customary to insert a stiffener between the outer layer of the shoe upper materials and the lining at the heel end of the shoe in assembling the upper materials on a last. This stiffener, commonly called a counter stiffener, may be premolded so that it retains a shape corresponding approximately to the heel end of the last and has at its lower edge an inturned flange by which it is attached to the insole of the shoe in the subsequent heel seat lasting operation. To prevent displacement, that is, creeping and wrinkling of the body of the counter between the outer layer of the shoe upper materials and lining during wear, it is customary to apply a coating of adhesive to both the inside and outside surfaces of the counter so that when the shoe upper is shaped to conform to the contour of the heel end of the last in the subsequent heel seat lasting operation, the outer layer and the lining will be caused permanently to adhere to the counter. In women's shoes a premolded counter of this type is extensively used. However, it has been found that the upper edge of the counter is too stiff and is likely to cause discomfort to the wearer of the finished shoe. This difficulty has been overcome by reducing the thickness of the upper edge of the counter as by skiving, although it has been found that if adhesive is applied to the reduced edge it tends to stiffen and harden it and thereby defeat the purpose for which the upper edge was reduced. Accordingly, it is proposed to leave the reduced or skived edge uncoated. The omission of adhesive along the skived marginal edge not only preserves its flexibility but also preserves the line-like thickness of the skived edge so that it does not show through on the outer face of the upper. It is also desirable to omit the adhesive from the flange along the bottom of the counter, since the flange is adequately secured in place by fastenings in the subsequent lasting operation. Moreover, the operator customarily grasps the counter by the flange in inserting it between the outer layer and the lining and, if the adhesive is omitted, it will not be transferred to the operator's hands and from them to the shoe upper.

An object of the present invention is to provide a semi-automatic adhesive applying machine by means of which the coating of articles, such as

5 premolded counters, may be quickly and effectively accomplished, provision being made for applying a coating to the central portion of the inside and outside surfaces of the counter and for preserving the top and bottom marginal edges free from coating material so that these edges will not become too stiff and cause discomfort to the wearer of the shoe.

To this end and in accordance with a feature of the invention, the adhesive applying machine includes an adhesive applicator and work presenting means for moving a premolded counter transversely of the applicator in a manner to apply adhesive first to one leg of the counter, then to the rounded rear end, and finally to the other leg of the counter. The aforesaid presenting means comprises a counter support movable transversely of the applicator and rotatable with respect to the applicator from a position in which one leg of the counter is brought into contact with the applicator to a position in which the other leg of the counter is carried over the applicator, and means for producing transverse and rotational movements of the support to coat progressively the whole length of the periphery of the counter. As illustrated herein, the support is rotatably mounted on a crosshead which is slidable transversely of the applicator. Adjacent to the crosshead there is driven means which is so 10 associated with the support that it may produce transverse movement of the crosshead or oscillations of the support. On the crosshead there is provided means for frictionally resisting rotation of the support so that normally the driven means moves the crosshead and the support as a unit transversely of the applicator. The oscillation of the support is effected by means for arresting the crosshead so that the driven means overcomes the frictional resistance to rotation and the support turns on the crosshead. As the turning of the support nears completion it renders the arresting means inoperative, whereupon the crosshead and support are again moved as a unit transversely of the applicator.

the applicator. The opposite marginal portion of the counter, which, as herein illustrated, is the inturned flange at the base thereof, is also protected from an application of adhesive by a holder, associated with the support, which is adapted to receive the flange and to hold it in an out-of-the-way position so that the applicator does not engage it during the movement with respect thereto. The counter support is moved from an initial position, at which position the clamping means is kept inoperative and the counter is placed upon the support, transversely of the applicator and back again to its original position, yieldable means being provided for holding the clamping means in engagement with the counter. The clamping means is released for engagement with the counter upon movement of the counter holder away from its initial position and, to permit removal of a counter which has been coated, retraction of the clamping means is effected by stop means located at the initial position of the support.

A further feature of the invention resides in means actuated by the transverse movement of the support for causing automatic reversal of its movement of translation and the stopping thereof at its initial position, other means being provided for latching the support at its initial position and for releasing said latching means manually, when initiating movement of the means for traversing the support.

These and other features of the invention will be best understood and appreciated from the following description of a preferred embodiment thereof described for the purpose of illustration and shown in the accompanying drawings, in which

Fig. 11 is a view on the line XI—XI of Fig. 10;

Fig. 12 is a vertical section through the crosshead and the frame showing the position of the parts when the crosshead is at its starting position; and

Fig. 13 is a similar view showing the crosshead at the other end of the frame and ready to reverse its transverse movement.

Referring to Figs. 1 and 10, the machine comprises, in general, a pair of applicator brushes 10 and 12 mounted upon parallel shafts 14 and 16 in such a manner that the tips of the brush bristles closest to each other just about touch, and a counter support 18 arranged to advance one of the legs of a premolded counter linearly in a substantially horizontal position between the bristles of the brushes until the counter has been advanced to a point where the crotch or rounded portion intermediate the legs engages the brush 12 which is at the inner side of the counter. When the counter has been moved relatively to the brushes to the position just described, linear movement of the counter is terminated and the counter is turned until its other leg is in a substantially horizontal position, whereupon the linear movement of the counter is continued in the same direction to draw this latter leg between the brushes. The movement of the counter support 18 is then reversed so that the counter is moved back between the brushes and to its original position and is, accordingly, given two coatings of adhesive. The applicator brushes 10 and 12 and the counter support 18 are mounted, together with mechanism for operating them, at the top of a base 20 (Fig. 1).

The parallel shafts 14 and 16 to which the applicator brushes are fastened are journaled in bearings 22 and 24 formed in a pedestal 26 which is fastened to the top of the base 20, as illustrated in Fig. 1. The pedestal 26 rises vertically and about midway of its height is bent rearwardly of the machine. The bearing 22 for the shaft 14 of the upper brush 10 is formed in the rearwardly bent portion of the pedestal in such a manner that it occupies a position rearwardly of the shaft 16 upon which the lower brush 12 is mounted, the bearing 24 for this latter shaft being formed in the unbent portion of the pedestal. Thus, the point at which the two brushes touch is located to the rear of and below the topmost point of the lower brush 12. This produces a better applying action, since the line of contact between the surface of the counter and the brushes is somewhat prolonged and the bristles of the brushes overlap without interference, yielding sufficiently to permit conformance to the shape of the counter (Fig. 10). The brushes 10 and 12 are driven in opposite directions by pulleys 28 and 30 (Fig. 1) mounted respectively upon the shafts 14 and 16. The pulleys 28 and 30 are connected for rotation to a sheave 32 having a number of grooves therein, by open and crossed belts 34 and 36, respectively. The sheave 32 is mounted for rotation on a shaft 38 journaled in a bracket 40 bolted to the base 20, the shaft 38 being driven by a pulley 42 fixed thereto, the latter being connected for rotation to the driven shaft 44 of a motor 46 by a belt 48. The upper brush 10, which is the larger of the two and serves to coat the outside surface of the counter, is about 6 1/4 inches in diameter and is driven in a counterclockwise direction, as seen in Fig. 1, at about 60 revolutions per minute. The smaller brush 12, which serves to coat the inside surface of the counter is about 2 1/2 inches in diameter and is driven in a clockwise direction at about the same peripheral speed as the brush 10. The brushes are about 1 1/2 inches wide and their bristles are relatively long and flexible so that they readily conform to the shape of the counter, as will be seen by reference to Fig. 10.

The adhesive is supplied to the larger brush 10 at its topmost point by an adhesive receptacle

50 (Fig. 3) supported above the brush by means not shown herein. An opening 54 is formed in the bottom of the receptacle past which the periphery of the brush moves, thereby causing the bristles to pick up adhesive which overflows through the opening, if the adhesive is fluid enough, or to rub on the adhesive in the opening. A slide 56 in the bottom of the receptacle 50 is provided for closing the opening 54 when the machine is not in operation. Sufficient adhesive is transferred to the smaller brush 12 by the larger brush 10 during periods when the counter is being placed upon the holder or removed therefrom to insure an adequate supply for coating the inside of the counter.

To effect the aforesaid linear and rotational movements of the counter, the counter support 18 is mounted for partial rotation or oscillation about a horizontal axis upon a crosshead 19, as will appear hereinafter, the crosshead being, in turn, slidably mounted upon a pair of parallel spaced rods 58 (Fig. 4). The rods 58 are supported in a horizontal position upon a rectangular frame 60 consisting of a pair of parallel spaced bars 62 joined by a transverse web 64. The rectangular frame 60 is fastened to the top of the base 20 in a horizontal position and runs from the front to the back of the machine, the front being at the left, as seen in Fig. 1. The forward ends of the rods 58 are fixed in bearing blocks 68 formed near the opposite ends of the transverse web 64. The rear ends of the rods 58 are fixed in bearing blocks 70 fixed to the transverse web 66 near its opposite ends.

The counter support 18 (Fig. 10) consists of two elements, a holding element 72, which is rotatably carried by an upright 74 rising from the crosshead 19 at the right side of the machine, as seen in Fig. 10, and a clamping element 76, which is rotatably carried by an upright 78 rising from the crosshead at the left side of the machine. The elements 72 and 76 are arranged to rotate on the crosshead about a common axis and, as will be seen by reference to Figs. 4, 5 and 10, comprise a pair of parallel spaced blocks 80 and 82. As viewed in side elevation (Figs. 5, 9 and 12), these blocks are substantially V-shaped, conforming substantially to the space bounded by the diverging legs of the counter C and adapted to receive the opposite marginal edges of the counter.

The counter holder 72 (Fig. 6) includes the substantially V-shaped block 80 which is provided on its left-hand face with a thin substantially V-shaped plate 84 secured by screws. The whole holder 72, including block 80, plate 84 and other parts to be described, has an axially extending recess 81 of V-shaped cross section to enable it to straddle the brush shaft 16 (Fig. 5). Alongside the plate 84 is a groove 86 adapted to receive the inwardly directed flange f of the counter when it is placed astride the block 80 and to hold the flange, as shown in Fig. 10, out of the way of the upper applicator brush 10, thereby preventing the application of adhesive thereto.

The holder 72 also has a flange 88 to which is fastened a pulley 92 which also has in it a substantially V-shaped recess 93 (Fig. 11) corresponding to and in line with the recess 81 (Fig. 5). The pulley 92 is provided with a pair of peripheral grooves 94 in each of which is secured an end portion of a chain 96, for a purpose which will appear hereinafter. The holder 72 and this pulley 92 are supported for partial rotation in a nearly

semicylindrical recess 98 formed in the top of the right-hand upright 74 with the pulley resting against one side of the upright and are held against axial movement therein by a disk 100 resting against the other side of the upright. In the disk 100 is a V-shape notch 102 (Figs. 5 and 6) to straddle the shaft 16. To keep this assembly 72, 92, 100 in the recess 98, the upright 74 has a rib 104 concentric with and just below the recess 98. This is received in a groove 106 on the inner face of the disk 100 and in a similar groove 106 in the inner face of the pulley 92.

The counter clamping element 76, which consists of the substantially V-shaped block 82 (Fig. 9), is fastened by screws 110 (Figs. 8 and 10) to a rectangular block 111 formed integral with the inner end of a shaft 112 journaled in a split bearing 114 formed at the top of the upright 78, the axis of rotation of the shaft 112 coinciding with the axis of rotation of the counter holder 72 and, at one time, with that of the lower brush shaft 16. A bolt 116 is passed through a pair of lugs 118 on the bearing 114 and has on one end interposed between its head and one of the lugs a spring 120. Hence, by rotation of a nut 122 on the other end of the bolt 116, the bearing 114 may be caused to exert a predetermined frictional resistance to rotary movement of the shaft 112 and the counter holder 72, for a purpose which will appear hereinafter. A pulley 124, which corresponds to the pulley 92, is also fastened to the shaft 112 and has formed in its peripheral surface two grooves 126 in each of which is secured the end of a chain 128.

The counter-supporting surface 130 of the V-shaped block 82 is beveled, with its inner periphery larger, as illustrated in Figs. 8 and 10, and the skived marginal portion of the counter is held against this sloping surface by means of a pair of clamps 132 (Fig. 8). The clamps 132 are so shaped that they extend along the beveled sides of the V-shaped block 82 from the rounded end thereof to the flared end (Figs. 8 and 9). Adjacent to the flared end of the block the clamps 132 are extended inwardly (Fig. 8) toward the supporting block 80, thus contacting the upper margin of the counter from a point near the rounded heel end thereof forwardly of the counter and part way around the curved forward ends. Each clamp 132 is fixed to a stem 134 which is pivotally mounted on a bracket 136 for rotation about a substantially horizontal axis parallel to that of the shaft 112, thereby permitting automatic adjustment of the clamps for variation in the thickness of the counter from front to back. The brackets 136 upon which the clamps are mounted are, in turn, pivotally mounted on the opposite ends of pins 138 for tilting about axes substantially at right angles to that of the shaft 112. The pins 138 are supported in bosses 139 formed on the shaft. A tension spring 140 (Fig. 9) is fastened to each of the brackets and to the block 82 and serves to urge the clamps 132 toward the sloping surface of the block 82 and, hence, to grip the counter thereagainst. A row of spike-like teeth 142 are provided along the edges of the clamps 132 (only one being shown on each clamp in Fig. 9) to aid in gripping the counter and preventing its movement in the clamping device. In order to release the counter from the clamping means after a coating of adhesive has been applied to it, means is provided for moving the clamps 132 away from the sloping surface of the V-shaped block 82 by tilting the brackets 136 about the pins 138. To this end, the brackets 136

have on them rollers 144 (Fig. 10) which are carried by legs 146 projecting from their undersides. The rollers 144 are adapted to be engaged by a wedge-shaped block 148 (Fig. 9) which is forked so that it may be slidably mounted upon the shaft 112 adjacent to the block 82, its legs being received in slots 150 formed in the shaft. The means, including a disk 266, for moving the wedge 148 in the slots 150 to separate the rollers 144 and thus to tip the clamps 132 away from the sloping surface of the block 82 will be described herein-after.

The crosshead 19, which supports the counter support 18, just described, for transverse and rotational movement with respect to the applicator brushes 10 and 12, is motivated as will now appear. The aforesaid chains 96 and 128, have ends which extend part way around and then are secured in the grooves of the pulleys 92 and 124. These chains pass over the top of these pulleys and to the left of the crosshead 19, as seen in Fig. 4, and around a pair of sprockets 152 and 154, thence lengthwise of the machine beneath the shafts 16 and 112, and around a pair of sprockets 156 and 158 and back over the tops and into the other grooves of the pulleys. The sprockets 152 and 154 are mounted for free rotation upon stub shafts 160 and 162, respectively, which are fixed in the upper ends of a pair of uprights 164, the latter being fastened by bolts 166 to the opposite parallel bars 62. The hole through which the upper bolt 166 of each pair passes is elongated (Fig. 1), thus permitting pivotal movement of the uprights each about the axis of its lower bolt 166. Short posts 168 are fastened to the parallel bars 62 (Fig. 4) behind each upright 164 and have on them adjusting screws 170 the ends of which bear against the uprights. By loosening the upper ones of the bolts 166 to release the uprights 164 and adjusting the position of the screws 170, the uprights 164 may be tilted to take up the slack in the chains 96 and 128. The sprockets 156 and 158 are fixed on a shaft 172, which is journaled for rotation between a pair of uprights 174, the latter being fastened to the parallel bars 62 at their lower ends. The shaft 172 has fixed thereto a gear 176 which meshes with a gear 178 fixed to a countershaft 180, the latter being journaled for rotation at its opposite ends between parallel upwardly extending webs 182 formed at the rear ends of the parallel bars 62 (Fig. 1). A drive pulley 184 is fixed on the countershaft 180 and may be connected by an open belt 186 (Fig. 1) or a crossed belt 188 to the sheave 32. Accordingly, when the countershaft 180 is rotated, the sprockets 156 and 158 drive their respective chains, which, in turn, produce linear movement of the crosshead 19 along the rods 58 past the applicator brushes 10 and 12 or rotational movement of the counter support 18 on the crosshead as will be later described.

Initially, the counter support 18 moves as a unit linearly in a manner to advance the open end of the counter toward the rear of the machine, at the right in Figs. 1, 4 and 13 and toward the applicator brushes and in such a position that one of the legs is substantially horizontal and passes between the brushes. The linear movement takes place because the crosshead is free to slide on the bars 58, and the counter support 18 is restrained from rotation on the crosshead by reason of the split bearing which is drawn up on the shaft 112 to create frictional resistance to rotation. The initial alinement of the counter support 18 on the crosshead, that is,

so that one leg of the counter is substantially horizontal, is established by a finger 190 (Fig. 5) which is formed on the disk 100 and which is arranged to co-operate with a recess 192 formed in a block 194 (Fig. 1) fixed to the top of a post 196 adjacent to the front end of the machine. The recess 192 has a wide mouth so that if the support and clamping means 18, in returning to its initial position, as will appear hereinafter, is slightly out of alinement, the finger 190 will be received by the recess 192 and the support 18 will be automatically brought into alinement thereby. As the crosshead advances, the counter straddles the brush 12 and finally a point is reached where the crotch of the counter is substantially in engagement with the brush shaft as shown in Figs. 1 and 5. It is to be observed that the brush shaft 16 extends across the machine directly in the path of the counter and the holder 72. Hence, in order that the crotch of the counter may be brought clear up to the brush, the holder 72, including the block 80, is provided with the substantially V-shaped recess 81 (Fig. 6), as hereinbefore described, so that the holder may also straddle the brush shaft. In like manner the substantially V-shaped recesses 93 (Fig. 11) and 102 (Fig. 6) are provided in the pulley 92 and disk 100, which, with the holder 72, constitute an integral unit, so that the unit may also straddle the brush shaft 16. Since the shaft 16 extends across the machine from one side only and the brush itself terminates short of the counter clamping means 76, the latter can be moved past the brush and therefore does not have a V-shaped recess. When the counter has been moved to the point where the crotch engages the bristles of the brush 12, it is oscillated in a clockwise direction, as viewed in Fig. 1, through approximately 135° about the axis of the brush, which brings the heretofore downwardly extending leg of the counter into a substantially horizontal position (Fig. 13) and reverses the position of the counter so that its open end now extends toward the front of the machine, i. e., the left in Fig. 1. This oscillation is accomplished as the crosshead 19 approaches the applicator brushes and the crotch of the counter comes into engagement with the brush 12, by one of a pair of levers 198, 198' (Fig. 5) which engages the crosshead and stops the linear movement of the crosshead transversely of the applicator brushes. The levers 198 and 198' are pivoted at 200 to one of the bars 62 and their lower ends are yieldably joined by means of a coil spring 202. The upper ends of the levers are beveled at 204 and have the resultant points cut off normal to the length of the levers leaving square ends. These are yieldably held by the spring 202 in engagement with a horizontal surface 206 formed on the underside of a bar 208 fastened to the crosshead 19. Notches are provided in the surface 206, thus forming opposed shoulders 210, one of which, as the crosshead is moved toward the right, will engage the square end of the right-hand lever 198 and prevent further transverse movement of the crosshead until some means is brought into operation to deflect the lever. Since the resistance to transverse movement of the crosshead 19 is now greater than the frictional resistance to rotation of the counter support 18, the chains 96 and 128, which heretofore produced transverse movement of the crosshead and which continue to be driven, turn the counter support 18 on the crosshead. At the same time the pulley 92 and disk 100, which are

secured to the counter support, are oscillated about the shaft 16 so that in their new position they lie on the opposite side of the shaft and the unit may be moved rearwardly without interference with the shaft. It is to be observed that the bearing recess 98 was made less than semi-cylindrical (Fig. 5), as heretofore noted, so that as the crosshead is moved past the shaft 16 the bearing can pass beneath the shaft without striking it.

Projecting radially from the disk 100 are a pair of lugs 212 (Fig. 5) through which there are adjustably threaded screws 214 and 214'. As the counter support and clamping means are rotated, the disk 100 is rotated with them and the screw 214, as illustrated in Fig. 6, will be moved into engagement with a cam block 216 fastened to the lever 198, at the left in Fig. 5, thereby deflecting the lever so that its square end is moved below the engaged shoulder 210. As soon as the lever 198 is moved out of contact with the shoulder 210, the crosshead resumes its transverse movement to the right-hand end of the machine, as seen in Fig. 1, thus drawing the uncoated leg of the counter between the applicator brushes 10 and 12, there being no further tendency to rotate the counter support 18 which is held frictionally. At this end of the machine a notched block 218 (Fig. 13), corresponding to the block 194, is provided for alining the other leg and side of the counter holding and clamping means 18 with the applicator brushes for its return movement by engagement of a finger 191 on the disk 100 with a notch 220 formed in the block 218. The forward movement of the crosshead is accomplished in exactly the same manner as the rearward movement and is initiated by the crosshead itself as it moves to the extreme right end of the machine, as will subsequently appear.

As previously explained, the driving pulley 184 (Fig. 4) may be connected to the sheave 32 by means of an open or a crossed belt. The open and crossed belts 186 and 188 are carried upon loose pulleys 222 and 224, respectively, mounted at opposite sides of the pulley 184 for free rotation upon the countershaft 180, each pulley being provided with two grooves 225, 226 and 227, 228. Below the pulleys 184, 222 and 224, parallel horizontally disposed rods 230 are fixed at their ends between the webs 182 and on these rods is slidably mounted for movement widthwise of the machine a belt shifter plate 232. Extending rearwardly of the plate 232 is a fork 234 which is adapted to engage the open belt 186, and extending forwardly from the plate 232 is a fork 236 adapted to engage the crossed belt 188. By movement of the plate 232 in one direction, one of the belts may be brought into engagement with the drive pulley 184 and at the same time the other belt may be moved into the groove of its pulley which is most remote from the pulley 184. The belt shifter plate 232 is operated by a bell-crank lever 238 pivoted at 240 to the frame of the machine, one end of the bell-crank lever being forked at 242 to receive a pin 244 fixed to the plate 232 and the other end being connected to an operating rod 246 which extends forwardly to the front of the machine where it may be grasped by the operator to move the bell-crank lever from one position to another in order to start the operation of the machine. The bell-crank lever 238 has connected thereto a tension spring 248 the opposite end of which is connected to one of the webs 182 in such a way that the line of center of the spring passes across the

75 pivot 240 when the bell crank is moved to either of its extreme positions, thus holding the bell crank in whichever position it is placed. When the rod 246 is pulled forwardly, the bell crank 238 will occupy the position shown in Fig. 4, and in this position the open belt 186 is in engagement with the pulley 184 and thus the sprockets 156 and 158 are driven in a clockwise direction and the chains are moving toward the right so that the crosshead 19 is moved toward the right. The crossed belt occupies the groove 226. As the crosshead approaches the extreme right position, a screw 250 threaded into the base thereof engages the bell crank 238 and moves it to its opposite position, thereby shifting the open belt 186 to the groove 228 of its pulley 222 and the crossed belt 188 from its pulley 224 to the pulley 184. The crossed belt reverses the rotation of the sprockets 156 and 158, and consequently the direction of movement of the chains 96 and 128, so that the crosshead is moved in the opposite direction, and the counter is coated a second time in the same manner that it was during its first transverse movement of the applicators. As the crosshead approaches its initial position, a projection 251 on the underside of the leading edge of the crosshead strikes a collar 262 on the rod 246 which shifts the crossed belt 188 into the groove 225 of its pulley 224 and the open belt 186 into the groove 227 of its pulley 222, and the machine automatically comes to a stop. At the same time a hook-like finger 254 (Figs. 2 and 12) which is carried by the crosshead engages a latch 256 pivotally mounted on a bracket 258 fastened to the web 64 of the frame 60 and retains the crosshead in its initial position until the machine is again started by pulling the rod 246 forward. The latch 256 is yieldably held in its operative position by a compression spring 260. 40 In order to release the latch when the machine is to be started, the collar 262 on the shifter rod has a pin 264 therein which lies in the path of the latch 256 and upon forward movement of the rod 246 will disengage the latch from the finger 254. This action is facilitated by the sloping position of the elongated arm 261 of the latch 256, said arm being guided and limited in its movement by engagement in a slot 263 in the bracket 258. 45 50 At the initial position of the crosshead 19 there is provided means for holding the clamps 132 in a retracted position to permit removal of a coated counter and the introduction of an uncoated counter. This consists of a disk 266 (Figs. 4, 8 and 9) carried by a yoke 268 which is supported by a threaded stem 270 on a bracket 272 fixed to the stub shaft 162 in such a position that the disk 266 will lie in the path of the wedge-shaped block 148 (Fig. 9) and force the latter inwardly between the rolls 144. A screw 273 provides means for adjusting the position of the bracket 272. As soon as the machine is started and the crosshead begins to move away from its initial position, the wedge-shaped block 148 moves out of contact with the disk 266, whereupon the springs 140 draw the clamp 132 against the counter and, in so doing, cause the rolls 144 to force the wedge-shaped block 148 back to an inoperative position on the block 111. 60 65 70 The machine, as described above, when set in motion, makes one complete cycle and then comes to a stop with the hook-like finger 254 held by the latch 256 and the belt shifter in neutral, whereupon it must be again set in motion. At rest, the counter support 18 is at the front or left

end of the machine; as seen in Fig. 12; and at this position the clamps 132 are held tilted away from the sides of the block 82 by engagement of the disk 266 with the wedge 148, as seen in Fig. 9. The operative may therefore readily place a premolded counter astride the blocks 80 and 82, setting the inturned lower edge thereof into the groove 86 on the block 80 and the skived upper edge against the sloping surface 130 of the block 82. At this initial position one side of the block 82 and one leg of the block 80 are substantially horizontal and the other side and leg slope downwardly and toward the rear of the machine. Having placed the counter on the blocks 80 and 82, the operative pulls the rod 246 forwardly, thereby releasing the latch 256 and shifting the open belt 186 onto the pulley 184, which, through gears, sprockets and chains heretofore described, begins to move the crosshead 19 rearwardly toward the applicator brushes 10 and 12. As the crosshead leaves its initial position, the wedge 148 moves out of engagement with the disk 266 and the clamps 132 are brought into engagement with the marginal edge of the counter by the springs 140, thereby securing the counter in place. The pulley 124 is fixed to the shaft 112 and the latter is frictionally clamped in its bearing 114 which may be tightened upon it by rotation of the nut 122. The frictional resistance to rotation of the shaft 112 is adjusted so that it is greater than the frictional resistance to transverse movement of the crosshead 19 on the rods 58. Hence, the movement of the chains 96 and 128 causes movement of the crosshead 19 and the counter support 18 as a single unit. This initial transverse movement advances one leg of the counter in a substantially horizontal position toward and between the applicator brushes 10 and 12 until the crotch of the counter is substantially in contact with the lower applicator brush 12. At this point the lever 198 engages a shoulder 210 on the crosshead and prevents further transverse movement of the crosshead. This added resistance to transverse movement is greater than the resistance to rotation of the shaft 112 and, consequently, as the chains continue to travel, the support 18 is rotated with the shaft 112 in a clockwise direction, as seen in Fig. 1, thus turning the counter and the assembly consisting of the V-shaped block 80, the pulley 92, and the disk 100 about the shaft 16 until the uncoated leg of the counter is in a substantially horizontal position. At this time, the screw 214 carried by the disk 100 comes into contact with the lever 198 and moves it out of engagement with the projection 210, whereupon the resistance to transverse movement becomes less than the resistance to rotational movement; and the crosshead resumes its transverse movement, drawing the newly positioned leg of the counter between the brushes. Near the end of the travel of the crosshead, the screw 250 (Fig. 13) carried thereby operates the belt shifting lever 238 which reverses the movement of the chains and causes the crosshead to travel back to the front of the machine in exactly the reverse manner that it traveled rearwardly, thus giving the counter a second coating of adhesive. The crosshead, as it returns to the front of the machine, strikes the collar 262 on the rod 246 with which the operative starts the machine, moving it to an inoperative position in which both the open belt 186 and the crossed belt 188 are on their respective loose pulleys, so that the machine comes to a stop. Simultaneously, the finger 254 is brought

into engagement with the latch 256 on the bracket 258, which locks the crosshead in its forward position until the rod 246 is again actuated by pulling it forward to start the machine.

5 This application is a continuation-in-part of our application Serial No. 495,748, filed July 22, 1943.

Having described our invention, what we claim as new and desire to secure by Letters Patent 10 of the United States is:

15 1. Apparatus for applying adhesive to a pre-molded counter having diverging legs, comprising an applicator, a movable support for a counter, and means for moving the counter support transversely of the applicator to advance first one leg of the counter across said applicator until the crotch between the legs is substantially in engagement with said applicator and then to turn the counter support and to draw the other leg across the applicator.

20 2. Apparatus for applying adhesive to a pre-molded counter having diverging legs, comprising an applicator, a movable support for a counter, means for moving the counter support transversely of the applicator to advance first one leg of the counter across said applicator until the bight between the legs is substantially in engagement with said applicator; and means for then rotating the counter support and moving it forward to draw the other leg across the applicator.

25 3. Apparatus for applying adhesive to a pre-molded counter having diverging legs joined by a rounded intermediate portion, comprising an applicator, a movable support for a counter, and means for moving the counter support transversely of the applicator in a manner to advance one leg of the counter across the applicator, then to turn the counter while holding the intermediate portion in engagement with the applicator, and finally to draw the other leg across the applicator.

30 4. Apparatus for applying adhesive to a pre-molded counter having diverging legs joined by a crotch, comprising a pair of applicators adapted to engage the opposite sides of an object passed between them, a movable support for a counter, and means for moving the counter support past said applicators to advance first one leg of the counter between said applicators until the crotch between the legs is substantially in engagement with one of the applicators and then to turn the counter support and to draw the other leg between the applicators.

35 5. Apparatus for applying adhesive to a pre-molded counter, comprising a pair of co-operating applicator brushes, means for rotating the brushes, means for supplying adhesive to one of said brushes, a counter support, means for imparting linear movement to the counter support to advance one leg of the counter between the brushes, and means to turn the counter support, said linear-movement-imparting means acting then to advance the other leg between the brushes.

40 6. Apparatus for applying adhesive to a pre-molded counter, comprising a pair of co-operating applicator brushes mounted for rotation on parallel shafts, said brushes having relatively long bristles, the shaft of one of said brushes being separated from the other by a distance which is less than the combined length of the bristles of the two brushes so that the bristles overlap, means for supplying adhesive to one of the brushes, a counter support, means for turning said support, and means for effecting linear movement of the counter support to advance one

leg of the counter between the brushes and then, after the counter has been turned, to draw the other leg between the brushes.

7. Apparatus for applying adhesive to a pre-molded counter having diverging legs joined at one end by a crotch, comprising a flexible applicator, and counter-supporting means movable bodily linearly to advance first one leg of the counter across the applicator, rotatable to turn the counter about its closed end, and finally reciprocable to draw the other leg across the applicator.

8. Apparatus for applying adhesive to a pre-molded counter, comprising an applicator, a support for the counter, means for moving the support transversely of the applicator, and means for effecting a change in the position of the support in timed relation to its traversing movement thereby to cause first one leg of the counter and then the other to be held in contact with the applicator.

9. Apparatus for applying adhesive to a pre-molded counter, comprising an applicator, a support for the counter movable transversely of the applicator and rotatable from a position in which one leg of the counter engages the applicator to a position in which the other leg engages the applicator, means for moving the support transversely of the applicator, and means associated with the support to cause said last-named means to rotate the support.

10. Apparatus for applying adhesive to a pre-molded counter, comprising an applicator, a crosshead mounted for movement transversely of the applicator, a support mounted for rotation on said crosshead from a position in which one leg of the counter engages the applicator to a position in which the other leg engages the applicator, and means for moving the crosshead transversely of the applicator and for rotating the support on the crosshead intermediate the travel of the crosshead.

11. Apparatus for applying adhesive to a pre-molded counter, comprising an applicator, a crosshead mounted for movement transversely of the applicator, a support rotatably mounted upon the crosshead for movement from a position in which one leg of the counter contacts the applicator to a position in which the other leg contacts the applicator, means co-operable with the support to cause transverse movement of the crosshead, and means arranged momentarily to arrest the crosshead intermediate its transverse movement, whereupon said means for causing transverse movement of the crosshead causes rotation of the support on the crosshead.

12. Apparatus for applying adhesive to a pre-molded counter, comprising an applicator, a crosshead movable transversely of the applicator, a support on said crosshead mounted for rotation from a position in which one leg of the counter lies in the plane of the applicator to a position in which the other leg of the counter lies in the plane of the applicator, means for imparting linear movement to the crosshead and rotational movement to the support, means for resisting rotation of the support to cause said last-named means to move the crosshead and support as a unit linearly to advance one leg across the applicator, an abutment on said crosshead, a lever arranged in the path of movement of the crosshead with an end thereof adapted to engage said abutment thereby to arrest the transverse movement of the crosshead and to cause said first-named means to rotate the sup-

port, and means for rendering said arresting means inoperative to permit said first-named means again to move the crosshead and support as a unit linearly thereby to draw the other leg of the counter across the applicator.

13. Apparatus for applying adhesive to a pre-molded counter, comprising an applicator, a support for the counter movable transversely of the applicator and rotatable from a position in which one leg of the counter engages the applicator to a position in which the other leg engages the applicator, means for imparting linear and rotational movement to the support, means for resisting rotational movement of the support to cause said first means to move the support linearly to advance one leg of the counter across the applicator, a cam surface on said support, a lever pivotally supported in the path of movement of the support with one end thereof held in engagement with said cam surface, an abutment on said cam surface arranged in co-operation with the end of the lever to arrest transverse movement of the support and to cause said first-named means to rotate the support, and means for rendering said arresting means inoperative to permit said first-named means again to move the support transversely thereby to draw the other leg across the applicator.

14. Apparatus for applying adhesive to a pre-molded counter, comprising an applicator, a support for the counter movable transversely of the applicator and rotatable from a position in which one leg of the counter engages the applicator to a position in which the other leg engages the applicator, means for imparting linear and rotational movement to the support, means for resisting rotation of the support to cause said first-named means to move the support linearly to advance one leg of the counter across the applicator, an abutment on said support, a lever arranged in the path of movement of the support, means for yieldably holding the lever in a position to engage said abutment thereby to arrest the transverse movement of the support and to cause said first-named means to rotate the support, and means for rendering said arresting means inoperative to permit said first-named means again to move the support linearly thereby to draw the other leg across the applicator.

15. Apparatus for applying adhesive to a pre-molded counter, comprising an applicator, a support for the counter movable transversely of the applicator and rotatable from a position in which one leg of the counter engages the applicator to a position in which the other leg engages the applicator, means for imparting linear and rotational movement to the support, means for resisting rotation of the support to cause said first-named means to move the support linearly to advance one leg of the counter across the applicator, an abutment on said support, a lever arranged in the path of movement of the support with one end thereof yieldably held in a position to engage said abutment thereby to arrest the transverse movement of the support and to cause said first-named means to rotate the support, and a finger associated with the support and movable therewith during its rotation, said finger being so located that it will engage said lever and depress it below said abutment to permit said first-named means again to move the support linearly thereby to draw the other leg across the applicator.

16. Apparatus for applying adhesive to a pre-molded counter, comprising an applicator, a sup-

port for the counter movable transversely of the applicator and rotatable from a position in which one leg of the counter engages the applicator to a position in which the other leg engages the applicator, means for imparting linear and rotational movement to the support, means for resisting rotation of the support to cause said first-named means to move the support linearly to advance one leg of the counter across the applicator, an abutment on said support, a lever arranged in the path of movement of the support with an end thereof adapted to engage said abutment thereby to arrest the transverse movement of the support whereupon said first-named means is effective to rotate the support, a cam plate fastened to said lever adjacent to its end, and an adjustable finger fixed to said support in such a position that near the end of the rotation of the support said finger will engage said cam plate and disengage the end of the lever from said abutment to permit said first-named means again to move the support linearly thereby to draw the other leg across the applicator.

17. Apparatus for applying adhesive to a pre-molded counter, comprising an applicator, a support for the counter movable transversely of the applicator and rotatable from a position in which one leg of the counter engages the applicator to a position in which the other leg engages the applicator, means for imparting reciprocal linear and rotational movement to the support, means for resisting rotation of the support to cause said first-named means to move the support linearly to advance one leg of the counter, during each traverse, across the applicator, a cam surface associated with the support, an abutment on said surface, a pair of levers pivotally mounted in the path of movement of the support with their ends opposed to each other, means for yieldably holding the ends of the levers in engagement with said cam surface to cause transverse movement of the support to be arrested in either direction by engagement of one or the other of the levers with said abutment whereupon said first-named means is effective to rotate the support, and a pair of fingers on said support arranged to engage one or the other of the levers as said support is rotated to one or the other of said positions to disengage the said lever and the abutment to permit said first-named means again to move the support linearly thereby to draw the other leg across the applicator.

18. Apparatus for applying adhesive to a pre-molded counter, comprising an applicator, a support for the counter movable transversely of the applicator and rotatable from a position in which one leg of the counter engages the applicator to a position in which the other leg engages the applicator, means for imparting reciprocal linear and rotational movement to the support, means for resisting rotation of the support to cause said first-named means to move the support linearly to advance one leg of the counter across the applicator during each traverse of the applicator, means for arresting the movement of the support in either direction of movement to cause said first-named means to rotate the support, and means for rendering said arresting means inoperative to permit said first-named means again to move the support linearly thereby to draw the other leg across the applicator.

19. Apparatus for applying adhesive to a pre-molded counter, comprising an applicator, a counter holder movable transversely of the applicator, a shaft for supporting said counter holder

for rotation about its axis from a position in which one leg of the counter is held in the plane of the applicator to a position in which the other leg of the counter is held in the plane of the applicator, and means for moving the counter holder transversely of the applicator, said means being operable to effect rotation of the holder about the axis of the shaft.

20. Apparatus for applying adhesive to a pre-molded counter, comprising an applicator, a counter holder, means including a shaft for supporting the counter holder for rotation about its axis from a position in which one leg of the counter is held in the plane of the applicator to a position in which the other leg of the counter is held in the plane of the applicator, a cross-head in which said shaft is journaled for rotation about its axis, said crosshead being mounted for movement transversely of the applicator, a pulley on said shaft, a chain associated with said pulley in a manner to produce linear movement of the crosshead and rotational movement of the shaft, means for driving the chain, a split bearing on said crosshead adapted frictionally to engage the shaft to resist rotation thereof to cause the chain to move the crosshead transversely thereby to advance one leg of the counter across the applicator, means for restraining the transverse movement of the crosshead to cause the chain to rotate the shaft in said split bearing to turn the counter, and means to render the restraining means inoperative to permit the chain again to move the crosshead transversely to draw the other leg across the applicator.

21. Apparatus for applying adhesive to a pre-molded counter, comprising an applicator, a counter holder, means including a shaft for supporting the counter holder for rotation about its axis from a position in which one leg of the counter is held in the plane of the applicator to a position in which the other leg of the counter is held in the plane of the applicator, a cross-head in which said shaft is journaled for rotation about its axis and for bodily movement transversely of the applicator with the cross-head, a pulley on said shaft, a chain associated with said pulley in a manner to produce linear and rotational movements thereof, means for driving the chain, means for frictionally holding said shaft from rotation to cause the chain to move the crosshead transversely thereby to advance one leg of the counter across the applicator, means for restraining the transverse movement of the crosshead whereupon the chain causes rotation of the shaft to turn the counter in spite of said friction means, and means to render the restraining means inoperative to permit the chain again to move the crosshead transversely to draw the other leg of the counter across the applicator.

22. Apparatus for applying adhesive to a pre-molded counter, comprising an applicator, a counter holder, means including a shaft for supporting the counter holder for rotation about its axis from a position in which one leg of the counter is held in the plane of the applicator to a position in which the other leg of the counter is held in the plane of the applicator, a cross-head in which said shaft is journaled for rotation about its axis and for bodily movement transversely of the applicator with the cross-head, means for effecting transverse movement of the crosshead thereby to advance one leg of the counter across the applicator, means for momentarily resisting the movement of the crosshead whereupon said first-named means effects rotation of

the shaft in the crosshead to turn the counter, and means for rendering said restraining means inoperative to permit said first-named means again to move the crosshead transversely to draw the other leg of the counter across the applicator.

23. Apparatus for applying adhesive to a pre-molded counter, comprising an applicator, a counter holder, means including a shaft for supporting said counter holder for movement transversely of the applicator and for rotational movement about the axis of the shaft to turn the counter holder from a position in which one leg of the counter is held in the plane of the applicator to a position in which the other leg of the counter is held in the plane of the applicator, means for frictionally engaging said shaft to prevent free rotation thereof, a pulley on said shaft, a chain co-operable therewith to impart transverse movement to the shaft and counter holder thereby to advance one leg of the counter across the applicator, means for resisting the transverse movement of the counter holder and the shaft in opposition to the feeding movement of the chain whereupon said frictional resistance to rotation of the shaft is overcome and said shaft and counter holder are caused to rotate thereby to turn the counter, and means on said counter holder to render said resisting means inoperative to permit said chain again to move the shaft and counter holder transversely to draw the other leg across the applicator.

24. Apparatus for applying adhesive to a pre-molded counter, comprising an applicator, a counter holder, means including a shaft for supporting said counter holder for movement transversely of the applicator and for rotational movement about the axis of the shaft to turn the counter holder from a position in which one leg of the counter is held in the plane of the applicator to a position in which the other leg of the counter is held in the plane of the applicator, a pulley on said shaft, a chain associated therewith to cause transverse movement of the shaft to advance one leg of the counter across the applicator, means to restrain the transverse movement of the shaft whereupon said chain causes rotation of the shaft to turn the counter, and means for rendering said restraining means ineffective to permit said chain again to move the shaft transversely to draw the other leg across the applicator.

25. Apparatus for applying adhesive to a pre-molded counter having diverging legs, comprising an applicator, a V-shaped member adapted to support the legs of the counter in their divergent position, means for initially holding said member with one leg in a plane passing through the applicator, means for moving the member transversely of the applicator to advance one leg of the counter across the applicator, means for arresting the transverse movement and effecting a rotation of the V-shaped member to bring its other leg into said plane after said first leg of the counter has traversed the applicator, and means for rendering said arresting means inoperative to permit said second means again to move the member transversely of the applicator thereby to draw the other leg of the counter across the applicator.

26. Apparatus for applying adhesive to a pre-molded counter, comprising an applicator, a support for the counter, means for engaging the counter along one edge to hold it on said support, means for moving the support transversely

of the applicator to advance one leg of the counter across the applicator, means for arresting the transverse movement and effecting a rotation of the support to turn the counter to bring the other leg into a position to engage the applicator, means for rendering said arresting means inoperative to permit said second means again to move the counter to draw the other leg across the applicator, and means for disengaging said first-named means at the end of the transverse movement of the support to release the counter.

27. Apparatus for applying adhesive to a pre-molded counter, comprising an applicator, a rotatable support for the counter also mounted for bodily movement, means for clamping the counter adjacent to one edge in engagement with the support, said means overlying the marginal portion of said edge from the rounded heel end forwardly along the legs and part way around the forward ends thereby protecting the same from an application of adhesive, means associated with the support adapted to receive the opposite marginal portion of the counter and to hold it at an angle to the body portion of the counter out of contact with the applicator, and means for imparting bodily and rotational movements to the support to advance one leg of the counter across the applicator to turn the counter and then to draw the other leg across the applicator.

28. Apparatus for applying adhesive to a pre-molded counter having a bottom flange, comprising an applicator, a movable support for the counter, said support including a pair of spaced members adapted to receive the opposite marginal edges of said counter, means associated with one of said members to receive the bottom flange, means associated with the other member for clamping the opposite marginal edge of the counter to said member, and means for imparting movement to the support to carry the periphery of the counter across the applicator.

29. Apparatus for applying adhesive to a pre-molded counter, comprising an applicator, a support for the counter, said support including a pair of spaced members rotatable on a common axis and adapted to receive the opposite marginal edges of said counter, means associated with said members to hold the opposite marginal portions of the counter at an angle to the body portion thereof, and means for imparting rotational movements to the support to turn the counter while in contact with the applicator.

30. Apparatus for applying adhesive to a pre-molded counter, comprising an applicator, a movable support for the counter, said support including a pair of spaced members adapted to receive the opposite marginal edges of said counter, means overlying one of said marginal portions from the rounded heel end forwardly along the legs and part way around the curved forward ends to shield said portion, and means for moving the support to present the periphery of the counter to the applicator for the coating of unshielded areas.

31. Apparatus for applying adhesive to a pre-molded counter, comprising an applicator, a counter holder movable from an initial position transversely of the applicator and back again, means associated with said holder for clamping the counter on said holder, said means being movable into engagement with the counter upon movement of the counter holder away from its initial position, means for yieldably holding said first means in engagement with the counter, and means for disengaging said first means as said

counter holder returns to its initial position to permit removal of the coated counter and introduction of an uncoated counter.

32. Apparatus for applying adhesive to a pre-molded counter, comprising an applicator, a counter holder movable from an initial position transversely of the applicator and back again, a pair of clamps co-operable with the holder to press the counter against the holder, said clamps being movable into engagement with the counter upon movement of the counter holder away from its initial position and being yieldable about axes at right angles to each other, means for yieldably urging said clamps toward the holder about one of said axes, and means for withdrawing and withholding the clamps as said counter holder returns to its initial position.

33. Apparatus for applying adhesive to a pre-molded counter, comprising an applicator, a counter holder movable from an initial position transversely of the applicator and back again, a pair of clamps adapted yieldably to engage the surface of the counter holder, said clamps being movable into engagement with the counter upon movement of the counter holder away from its initial position, a wedge slidably mounted on said support in a position to be moved between said clamps and to lift them out of engagement with the surface of the counter holder, and means at the initial position for moving the wedge between said clamps as the counter holder returns to its initial position.

34. Apparatus for applying adhesive to a pre-molded counter, comprising an applicator, a counter holder movable from an initial position transversely of the applicator and back again, a pair of clamps adapted to engage the surface of the counter holder, said clamps being movable into engagement with the counter upon movement of the counter holder away from its initial position, spring means for yieldably urging the clamps toward said counter holder, a roller on each clamp, a wedge slidably mounted on said support for movement between said rolls thereby to lift the clamps out of engagement with said surface, and an abutment at the initial position adapted to engage said wedge as said support returns to its initial position and to force it between said rolls, said springs being of sufficient strength to force the wedge from between the rolls when said counter holder moves away from said initial position.

35. Apparatus for applying adhesive to a pre-molded counter, comprising an applicator, a crosshead mounted for movement transversely of the applicator, a support for the counter mounted on the crosshead, said support including a pair of spaced members adapted to receive the opposite marginal edges of the counter, said spaced members being mounted for rotation on the crosshead about a common axis, a pulley block fixed to each member, a pair of endless chains mounted upon carriers at opposite sides of the pulley blocks, the opposite ends of each chain being fastened to one of the pulley blocks, means to cause one of the pulley blocks to resist rotation to cause said chain to move said crosshead longitudinally of the applicator, means intermediate the transverse movement of the crosshead to prevent further movement thereof to cause said chain to rotate the support on the crosshead, and means actuated by the rotation of the crosshead to render said last-named means inoperative to permit said chain again to move the crosshead transversely.

36. Apparatus for applying adhesive to a pre-molded counter, comprising an applicator, a frame, a crosshead slidable along said frame transversely of the applicator, a support for the counter mounted on the crosshead, said support including a pair of spaced members adapted to receive the opposite marginal edges of the counter, said spaced members being mounted for rotation on the crosshead about a common axis, a pulley block fixed to each member, a pair of carriers at opposite ends of the frame, a pair of chains mounted between said carriers with their opposite ends fastened to said pulley blocks, means for driving one pair of carriers thereby to traverse the chains, friction means for preventing rotation of one of the pulley blocks to cause movement of the chains to produce movement of the crosshead along the frame, means for producing greater frictional resistance to movement of the crosshead along the frame than the frictional resistance to rotation to cause said chains to rotate the support, and means for rendering said means for producing resistance to longitudinal movement inoperative to permit said chains again to produce transverse movement of the crosshead.

37. Apparatus for applying adhesive to a pre-molded counter, comprising an applicator, a rotatable support for the counter, reversible means for moving the support transversely of the applicator in one direction, and rotatively, to present first one leg of the counter and then the other leg to the applicator, and means associated with said support for acting on said moving means to reverse the direction of movement of the support to cause the legs of the counter to retraverse said applicator.

38. Apparatus for applying adhesive to a pre-molded counter, comprising an applicator, a crosshead, a support for the counter rotatable on said crosshead, power-operated means for moving the support transversely of the applicator first in one direction and then in the opposite direction to cause said support to advance one leg of the counter across said applicator and then the other leg in each traversing movement of the support, manual means for starting said power-operated means in operation, and automatic means for controlling said power-operated means to reverse the direction of movement of the support and to bring said power-operated means to a stop when the support is returned to its initial position.

39. Apparatus for applying adhesive to a pre-molded counter, comprising an applicator, a crosshead, a support for the counter rotatable on said crosshead, power-operated means for moving the support transversely of the applicator first in one direction and then in the opposite direction to cause said support to advance one leg of the counter across said applicator and then the other leg in each traversing movement of the support, manual means for starting said power-operated means in operation, and means controlled by the support for reversing said power-operated means and for bringing said power-operated means to a stop when the support is returned to its initial position.

40. Apparatus for applying adhesive to a pre-molded counter having diverging legs, comprising a rotary applicator, a counter holder having diverging legs along which the legs of the counter lie, means for supporting the counter holder for rotation from a position in which one leg of the counter holder is held in a plane substantially

tangent to the periphery of the applicator to a position in which the other leg of the counter holder is held in said plane, means for moving the counter holder transversely of the applicator, means for effecting rotation thereof, and means coacting with said counter holder to turn it into one of said positions at the end of a transverse movement.

41. Apparatus for applying adhesive to a pre-molded counter, comprising an applicator, a support for the counter, means for reciprocating the support transversely of the applicator, said support being adapted to hold first one leg of the counter and then the other in a position to contact the applicator during its transverse movement and to effect said change in position of the support to bring one or the other of the legs into contact with the applicator, and means for engaging said support after it has made one cycle of its movement for retaining it in its initial position.

42. Apparatus for applying adhesive to a pre-molded counter, comprising an applicator, a support for the counter, means for reciprocating the support transversely of the applicator, said support being adapted to hold first one leg of the counter and then the other in a position to contact the applicator during each traversing movement and to effect said change in position of the support, means for starting reciprocation of said first-named means, means for terminating the reciprocation of the first-named means after one cycle, and means for latching said support in its initial position, said latching means being operable to release the support by actuation of said means for starting reciprocation of said first-named means.

FRED RICKS,
CHARLES MARTIN BAGSHAW.
